Primary Examiner — Kimberly Barnes(74) *Attorney, Agent, or Firm* — Hoglund & Pamias,
PSC; Roberto J. Rios(57) **CLAIM**

The ornamental design for a facial mask support, as shown and described.

DESCRIPTION

FIG. 1 is a top front right perspective view of a facial mask support showing my new design, the top front left perspective view being a mirror image thereof;

FIG. 2 is a front view of FIG. 1;

FIG. 3 is a rear view of FIG. 1;

FIG. 4 is a right view of FIG. 1;

FIG. 5 is a left view of FIG. 1;

FIG. 6 is a top view of FIG. 1; and,

FIG. 7 is a bottom view of FIG. 1.

1 Claim, 7 Drawing Sheets(56)
